[57] CLAIM

An ornamental design for a dispenser head for caulking gun,
as shown and described.

DESCRIPTION

FIG. 1 is a perspective view of the design of the dispenser
head for caulking gun;

FIG. 2 is a top plan view thereof;

FIG. 3 is an end view thereof as seen from the left hand side
of FIG. 2;

FIG. 4 is an end elevational view thereof as seen from the
right hand side of FIG. 2;

FIG. 5 is a side elevational view thereof;

FIG. 6 is the other side elevational view thereof; and,

FIG. 7 is a bottom plan view thereof.
